CLAIM

I claim the ornamental design for a garment with internal pockets, as shown and described.

DESCRIPTION

FIG. 1 is a perspective view of a garment with internal pockets, showing my new design in a closed configuration;
 FIG. 2 is a front elevational view of FIG. 1;
 FIG. 3 is a rear elevational view of FIG. 1;
 FIG. 4 is a right-side elevational view of FIG. 1;
 FIG. 5 is a left-side elevational view of FIG. 1;
 FIG. 6 is a top plan view of FIG. 1;
 FIG. 7 is a bottom plan view of FIG. 1;
 FIG. 8 is a perspective view of the design in a partially open configuration; and,
 FIG. 9 is a front elevational view of FIG. 8.
